UNITED STATES PATENT OFFICE.

GUYON MILLER, OF DOWNTON, PENNSYLVANIA, ASSIGNOR TO DOWNTON MANUFACTURING COMPANY, OF DOWNTON, PENNSYLVANIA, A CORPORATION OF PENNSYLVANIA.

ROLL FOR BEATING-ENGINES.

1,138,393.

Specification of Letters Patent.

Patented May 4, 1915.

Application filed January 27, 1910. Serial No. 540,341.

To all whom it may concern:

Be it known that I, GUYON MILLER, a citizen of the United States, residing in Downton, Pennsylvania, have invented 5 certain Improvements in Rolls for Beating-Engines, of which the following is a specification.

My invention relates to certain improvements in means for retaining the blades of 10 the rolls of beating engines used to reduce paper and other stock to pulp.

The object of my invention is to simplify 15 the construction of the blades and the mechanism by which they are held to the carrying heads, whereby the blades can be readily assembled on the heads, or removed therefrom in the case of repairs.

In the accompanying drawings:—Figure 1, is an end view of a portion of an engine 20 beating roll illustrating my invention; Fig. 2, is a transverse sectional view on the line 2—2, Fig. 1, illustrating the full diameter of the roll; Fig. 3, is a sectional view on the line 3—3, Fig. 2; Fig. 4, is a sectional view 25 on the line 4—4, Fig. 2; Fig. 5, is a perspective view of a portion of one of the blades; Fig. 6, is a perspective view of a portion of one of the end heads; and Fig. 7, is a diagram view of one of the blades illustrating 30 one of the features of my invention.

A is a shaft which is mounted in suitable bearings in the beating engine.

B, B are the end heads of the roll and 35 B', B' are the intermediate heads, suitably secured to the shaft A. The heads have flanges b in which is a series of dovetailed grooves b', clearly illustrated in Fig. 6.

D, D are the blades. The body portion of 40 each blade is of an even thickness throughout, with the exception that at intervals I form tapered projections d at one side of each blade, as illustrated in Fig. 5. These projections are spaced apart so as to aline 45 with the heads B, B' when they are in position. The outer ends d' of the blades are slightly beveled on one side, as shown, so that the blades are comparatively narrow at the cutting edges d.

It will be noticed in Fig. 7, that the sides

of the dovetailed slots b' in each head are 50 equi-distant from a center line x radiating from the center of the shaft A. This construction throws the working face d² of each blade on a slight angle in respect to the radial line x, causing the pulp to more readily 55 free itself from the blade. By this construction the blade can be reversed and may be applied to a roll running in one direction or the other. The roll itself is interchangeable, owing to this construction.

In order to fasten the blades firmly to 60 their heads and prevent any longitudinal movement of the heads, I provide wedge shaped wooden blocks E, which are forced into the space between the blades and between the heads. These blocks preferably extend beyond the inner ends of the blades and interlock, due to the swelling of the blocks when they become wet. I also mount blocks F between each of the blades, these 65 blocks extend from one end of the roll to the other and form the base of the gullet between the blades.

By the above construction I am enabled to 70 make a roll which is economical to manufacture and which can be readily assembled and the parts can be quickly removed when 75 repairs are necessary.

The blades, when placed in position, are 80 dropped in the proper space so that the wedges clear the heads and by a slight longitudinal movement of the blade each wedge-shaped section is drawn tightly into its position in its respective head, after which the blocks are placed in position; securely locking the parts together.

I claim:—

The combination in a beating roll, of a 90 shaft; heads mounted on the shaft, said heads having flanges in which are a series of dove-tailed grooves, the walls of each of 95 said grooves being equi-distant from a radial line taken from the center of the roll; a series of reversible blades adapted to fit the dove-tailed grooves, each of said blades having one side straight from top to bottom and each blade having spaced projections at the bottom of the opposite side, said projections

being tapered and the outer portion of the side of the blade having said projections being beveled to impart a slight cant to the working face of the blade with respect to the radial line of said blade; and filling blocks mounted between said blades.

In testimony whereof, I have signed my

name to this specification, in the presence of two subscribing witnesses.

GUYON MILLER.
